INVENTOR

Thomas T. Parker

BY J. P. V. & CO.

ATTORNEY

UNITED STATES PATENT OFFICE.

THOMAS T. PARKER, OF BROOKLYN, NEW YORK.

STEAM-BOILER.

1,294,836.

Specification of Letters Patent. Patented Feb. 18, 1919.

Application filed September 7, 1918. Serial No. 252,995.

To all whom it may concern:

Be it known that I, THOMAS T. PARKER, a citizen of the United States, and resident of the city of New York, borough of Brooklyn, in the county of Kings and State of New York, have invented certain new and useful Improvements in Steam-Boilers, of which the following is a specification.

This invention concerns a modification and improvement of the feed-water structure forming the subject of my Letters Patent of the United States No. 1,224,862, dated May 1, 1917, to which reference may be had; the object of my present invention being to insure a more rapid and effective preheating of the feed-water than in the previous structure, and also to facilitate the operation of inspecting and cleaning the apparatus.

The feed-water structure disclosed in the said patent is illustrated as installed in a horizontal steam boiler of the steam-and-water drum type, while the improved structure is herein shown in connection with a boiler of the fire-tube type; but the particular type of boiler with which the feed-water structure, in either instance, is employed is immaterial so far as the principle of operation of the apparatus is concerned.

My previous construction above referred to includes an open-top main receptacle supported within the boiler drum, which receptacle has at one end a feed-water outlet located above the normal boiler-water level and provided with a depending protective shield; and an auxiliary open-top elongated receptacle supported within and above the bottom of the main receptacle, and being closed at that end adjacent the said outlet and open at the opposite end, said auxiliary receptacle having therein a supplemental chamber to which the feed-water is initially delivered by a supply pipe depending into the chamber, whereby the water introduced to said chamber serves as a seal for the pipe and at the same time overflows into the main chamber of the auxiliary receptacle, passing thence to the open end of the latter, entering the main feed chamber, and escaping finally through the said outlet into the boiler proper, such water in its prolonged passage through the receptacles being preheated, as and for the purpose fully set out in the patent aforesaid.

According to the main feature of my present invention the supplemental water-seal chamber is constituted by a primary recep-

tacle, preferably of shallow trough-like form, which is supported within the auxiliary receptacle in such a manner as to project above the latter and deliver the water thereto in extended film-like streams which are exposed to the direct action of the hot steam circulating about the primary receptacle, the water in its passage to the auxiliary receptacle thus being preheated to a high degree.

My invention also comprises various features of construction and arrangements of parts whereby practical advantages are secured, all as will be hereinafter described and claimed.

In the drawings—

Figure 1 is a longitudinal vertical section of one end portion of a horizontal steam boiler of the fire-tube type, equipped with a feed-water structure embodying the preferred form of my invention.

Figs. 2 and 3 are partial transverse vertical sections as on the lines 2 and 3, respectively, of Fig. 1.

Fig. 4 is a sectional plan of the structure as on the line 4—4 of Fig. 3.

Fig. 5 is a transverse section, enlarged, through the primary receptacle, and adjuncts, as on the line 5—5 of Fig. 4.

Fig. 6 is a partial vertical section, also enlarged, of the discharge end of the structure.

Referring to the drawings, 5 designates a portion of the cylindrical shell of a horizontal steam boiler; 6 one of the end heads; 7 rows of fire tubes within the shell, and 8 inclined brace bars between the head and the top of the shell, all such parts being of any usual or approved construction.

My improved feed-water structure is located within the shell, and when it is applied to a fire-tube boiler as herein illustrated, it is positioned adjacent the end head 6 and directly above the upper row of fire tubes. The structure, in its preferred form, comprises a main feed-water receptacle, including a bottom plate 9 which extends from side to side of the shell and is secured thereto and to the end head; the longitudinal edges 10 and the rear end of the plate being provided with flanges 10 which are riveted or otherwise appropriately fastened to the shell and head, respectively, as shown. This head constitutes one end of the main feed-water receptacle, the sides of which are constituted by the shell. The other end of the recep-

tacle is comprised by an upstanding transversely extending wall plate 11 having its ends formed to correspond with the curvature of the shell. This plate is detachably secured, preferably by means of bolts and nuts, 12, to suitably disposed angle strips 13 riveted to the shell and bottom plate, appropriate gasket material being interposed between the plate and the angle strips in order 10 to insure a water-tight joint.

The upper edge of the end wall plate 11 lies somewhat below the top of the shell to afford direct communication between the steam space of the boiler (above the normal 15 water level) and the open unobstructed top of the feed-water chamber constituted by the main receptacle, whereby the steam generated within the boiler proper is free to circulate above and in contact with the 20 tents of said chamber.

In the end plate 11, near its upper edge, is a feed-water outlet 14, preferably in the form of an elongated slot, and on the inner side of the plate is affixed, adjacent the outlet, a depending plate 13 which constitutes a shield or trap to prevent the passage of 25 floating substances to the outlet.

In the preferred form of my invention herein illustrated that end of the bottom 30 member which is affixed to the boiler-head 6 is slightly below the normal water level of the boiler proper, and is inclined upwardly therefrom to the water level, as shown, whereby such member is partially 35 submerged in the hot boiler water, and the feed-water contained in the chamber is therefore subjected to the influence of the heat from the boiler water.

An auxiliary water receptacle is affixed to 40 standards rising from the bottom of the main feed-water chamber, which receptacle is of less depth, length and width than said chamber so as to leave ample water space between the two receptacles. This auxiliary 45 receptacle, in its preferred form, comprises a bottom 16, sides 17, and an end wall 18 adjacent the slotted wall 11 of the main receptacle, the opposite end of the auxiliary receptacle being open and unobstructed as 50 shown.

Suspended within the auxiliary receptacle, in spaced relation to the walls of the latter, is a primary water receptacle, comprising, an elongated body portion 19, substantially semicircular in cross-section, having end walls 20 which rise somewhat higher than the lateral edges of the body portion. The body is provided with pairs of laterally projecting lugs 21 55 which are arranged to rest in suitably-disposed notches in the upper edges of the side walls of the auxiliary receptacle and thereby detachably support the primary receptacle in position adjacent the end wall of the 60 auxiliary receptacle and above the bottom

of the latter. When the primary receptacle is thus supported its lateral edges extend well above the sides of the auxiliary receptacle and the water level prescribed by the egress slot in the end wall of the main feed-water chamber. A feed-water pipe 22 depends into the primary receptacle, and a blow-off pipe 23 rises from the said chamber. 70

By the foregoing described construction it will be seen that water delivered to the 75 primary receptacle by the pipe 22 rises in and overflows both sides of such receptacle, gravitating in extended films or streams down the curved exterior of the body 19, and escaping thence to the auxiliary receptacle. Thereupon the water flows along the auxiliary receptacle, enters the main chamber and reversely travels slowly along the latter. When the supply of feed-water 80 reaches the level of the outlet 14 the water flows through the latter into the boiler proper as above mentioned.

It is to be noted that the water flowing 85 from the sides of the body 19 to the auxiliary receptacle is exposed to a bath of live steam, and since this water is in film-like streams the preheating of the water is materially facilitated. This is an important feature of 90 my invention. During the subsequent flow 95 of the water through the main and auxiliary receptacles the temperature of the feed-water is further raised not only by the prolonged action of the steam thereon but by the heat absorbed by the water from the bottom of the main receptacle. 100

As described in my previous patent the hot-feed water dissolves the soluble substances therein, the heavier matter dropping to the bottoms of the receptacles and 105 the lighter matter rising to the surface of the feed-water. The accretions of floating substances, which are prevented by the shield from escaping through the outlet into the boiler proper, finally fall to the bottom of 110 the main receptacle, whence they, together with the water contents of the main and auxiliary receptacles, may be readily expelled from time to time through the blow-off pipe. 115

The primary receptacle, as I have termed it, not only performs the important function of discharging the water therefrom in divided film-like streams which are subjected to the efficient action of the hot steam as 120 above explained, but the water within the primary receptacle insures for the delivery end of the feed-pipe an efficient seal which prevents the entry of steam into said pipe.

As the end wall plate 11 of the main receptacle is readily removable, by manipulation of its bolt and nut connections, access can be readily had to the interior of the structure for inspection and cleaning. The removal of this end plate also facilitates the 125

ready withdrawal and replacement of the primary receptacle as occasion may require.

It is to be understood that my invention is not limited to the specific details of construction herein disclosed, as the same may be modified within the principle of the invention and the scope of the appended claims.

I claim—

- 10 1. In a horizontal steam-boiler, an open-top main receptacle within the same having at one end a feed-water outlet located above the normal boiler-water level, an auxiliary open-top elongated receptacle supported within the main receptacle above the bottom of the latter, said auxiliary receptacle being closed at that end adjacent the said outlet and open at the opposite end, a primary receptacle supported within said auxiliary receptacle and spaced from the walls of the latter, the sides of said primary receptacle extending above the said outlet, and means for supplying feed-water to said primary receptacle.
- 15 2. In a horizontal steam-boiler, an open-top main receptacle within the same having at one end a feed-water outlet located above the normal boiler-water level, an auxiliary open-top elongated receptacle supported within the main receptacle above the bottom of the latter, said auxiliary receptacle being closed at that end adjacent the said outlet and open at the opposite end, a primary receptacle supported within said auxiliary receptacle and spaced from the walls of the latter, the ends and sides of said primary receptacle extending above the said outlet, the ends being higher than the sides, and means for supplying feed-water to said primary receptacle.
- 20 3. In a horizontal steam-boiler, an open-top main receptacle within the same having at one end a feed-water outlet located above the normal boiler-water level, an auxiliary open-top elongated receptacle supported within the main receptacle above the bottom of the latter, said auxiliary receptacle being closed at that end adjacent the said outlet and open at the opposite end, a primary receptacle supported within said auxiliary receptacle and having lateral overflow portions above the said outlet, and means extending into said primary receptacle for supplying feed-water thereto.

receptacle removably supported on said auxiliary receptacle adjacent the closed end of the latter so as to lie partly within and partly above the auxiliary receptacle, and means for supplying feed-water to said primary receptacle.

4. In a horizontal steam-boiler including a shell and end head, a main feed-water receptacle adjacent said head, comprising a bottom member extending from side to side of the shell and secured thereto and to the head, a transverse wall arranged at the inner end of the bottom member and detachably secured thereto and to the shell, said wall terminating short of the top of the shell and having a water outlet above the normal boiler-water level, an auxiliary open-top elongated receptacle supported within the main receptacle above the bottom of the latter, said auxiliary receptacle being closed at that end adjacent the said outlet and being open at the opposite end, and means for delivering feed-water to the said auxiliary receptacle.

5. In a horizontal steam-boiler including a shell and end head, a main feed-water receptacle adjacent said head, comprising a bottom member extending from side to side of the shell and secured thereto and to the head, a transverse wall arranged at the inner end of the bottom member and detachably secured thereto and to the shell, said wall terminating short of the top of the shell and having a water outlet above the normal boiler-water level, an auxiliary open-top elongated receptacle supported within the main receptacle above the bottom of the latter, said auxiliary receptacle being closed at that end adjacent the said outlet and open at the opposite end, a primary receptacle supported within said auxiliary receptacle and having lateral overflow portions above the said outlet, and means extending into said primary receptacle for supplying feed-water thereto.

Signed at New York, in the county and State of New York this 30th day of August, A. D. 1918.

THOMAS T. PARKER.
